COLLAPSIBLE CLOTHES DRYER

Robert D. Raynor, 7810 Corbin, Reseda, Calif.
Filed Aug. 27, 1962, Ser. No. 219,398
7 Claims. (Cl. 211—178)

Generally speaking, the present invention comprises a controllably expandable and collapsible rack and, more particularly, in one specific preferred form of the invention, comprises a controllably expandable and collapsible clothes hanging rack from which a plurality of freshly washed clothes may be supported or hung to allow ambient atmosphere to have free access thereto for the purpose of drying the clothes. Of course, this may also apply to clothes which have been cleaned by a cleaning fluid and which also need to be aired in a manner similar to the drying of freshly washed clothing or the like.

Incidentally, the terms "clothes" and "clothing" are to be broadly construed as including virtually any other articles which may require airing or drying.

A particular and very significant advantage of the controllably expandable and collapsible clothes hanging rack of the present invention lies in the fact that it includes two separate and individually operable slidables collars or rings, each one of which is independently slideable and adapted to erect or collapse one-half of all of the expandable elements of the rack. This makes it possible to erect or collapse the expandable elements of the rack in two distinct steps, thus greatly reducing the force which must be applied to each of said slideable collars or rings during the rack-expanding or rack-collapsing operation. This effective splitting of the opening operation and the closing operation into two parts is an extremely important feature of the present invention which may, as a result of this operative feature, be termed a double action expandable and collapsible rack.

Furthermore, it should be noted that the novel controllably expandable and collapsible clothes hanging rack of the present invention is adapted for outdoor or indoor use by being provided with appropriate supporting base means, or the like, for effective engagement with respect to an underlying supporting surface such as a horizontal ground surface (which is intended to mean an outdoor ground surface whether of earth, turf, concrete, asphalt, or the like, and which is also intended to mean an indoor ground surface such as a floor of any suitable composition within a house, apartment, building, or any other structure). The invention itself lies primarily in the novel collapsible and expandable structure of the rack irrespective of the type of ground surface-engageable supporting base means.

It is an object of the present invention to provide a novel controllably expandable and collapsible rack (primarily intended for clothes hanging use, although not specifically limited thereto) which comprises a longitudinal, normally upright support member or standard provided with a lower portion (usually the bottom end) adapted to be rigidly supported relative to an auxiliary supporting means (usually a ground surface whether of an outdoor type or an indoor type comprising a floor or the like) in a firm, stable relationship with respect to said auxiliary supporting means.

The normally upright supporting member or standard is pivotally provided with a plurality (usually a first and second set of two each) of longitudinal rigid fulcrum members each having a pivotal fulcrum connection means spaced from the pivotal connection of the fulcrum member with respect to the upright support member or standard by a given distance equal in the case of each of said fulcrum members.

The preferred embodiment of the invention may also include first and second sets of lever members (usually

2

with two lever members to each set) having inner pivotal connection ends, outer linkage ends, and intermediate fulcrum connection means-engageable portions, and may also be provided with first and second slideable collar or ring means pivotally connected to the inner pivotal connection ends of the corresponding members of the corresponding set of said lever members. In other words, said first slideable collar or ring means is connected to the inner pivotal connection ends of said first set of lever members and said second slideable collar or ring means is connected to said inner pivotal connection ends of said second set of lever members, with said first and second slideable collar or ring means being slidably mounted on an intermediate portion of said vertically upright support member or standard for reciprocation between the maximum limits of the longitudinally spaced-apart relationship of said slideable collars or ring means when the rack is in fully collapsed relationship and the closely vertically adjacent central positions of said slideable collars or ring means on said vertical upright support member or standard when said rack is in fully expanded relationship.

This preferred form of the invention may also include controllably releasably retaining means for retaining said first and second slideable collar or ring means in said vertically adjacent centrally positioned relationship until controllably released to allow collapsing of the entire rack.

In the preferred form of the invention, one-half of the plurality of fulcrum members (usually the two fulcrum members of either said first or second set thereof) have their pivotal fulcrum connection means at the outer ends thereof pivotally connected to the intermediate fulcrum connection means-engageable portion of the corresponding lever members (usually the corresponding two lever members of the corresponding one of said first and second sets thereof). Also, in said preferred form of the invention the other half of said plurality of fulcrum members (usually the two fulcrum members of the other set of said fulcrum members) have the pivotal connection fulcrum means at the outer ends thereof connected to the intermediate fulcrum connection means-engageable portions of the corresponding ones of the remaining lever members (usually the two lever members of the remaining set of said lever members) on the opposite side of said upright vertical support member or standard from the connections of said first-mentioned pivotal connection fulcrum means and said first-mentioned intermediate fulcrum connection means-engageable portions of said first-mentioned set of fulcrum means and said first-mentioned set of said lever members whereby forcible slideable reciprocation of one of said two slideable collar or ring means in an upward direction along said upright vertical support member or standard away from the other one of said collar or ring means will cause pivotal and inward swinging and effective collapsing movement of the corresponding set of said lever members (one of said two sets thereof) in a similar rotative angular sense, and whereby oppositely directed downward slideable movement of the other one of said two slideable collar or ring means along said upright support member or standard and away from said first-mentioned collar or ring means will cause pivotal upward and inward swinging and effective collapsing movement of the other corresponding set of said pivotal lever members in a similar rotative angular sense opposite to said first-mentioned rotative angular sense of said first-mentioned set of pivotal lever members.

Of course, it should be understood that opposite reciprocation of said collars or rings toward each other will reverse the above described lever-swinging movements and will effectively expand the rack.

Also, in the preferred form of the invention, the rack may include first and second tensile member support bars adapted to be provided with a plurality of tensile members

connected therebetween. Each of said tensile member support bars is provided with connection means adjacent opposite ends thereof effectively pivotally connected to the corresponding outer linkage ends of a pair of lever members comprising corresponding similar members of different ones of said two sets of lever members whereby similar ends of each of said tensile member support bars will be connected to corresponding outer linkage ends of different ones of the same set of said lever members and whereby opposite ends of said tensile member support bars will be connected to different but corresponding ones of the two different sets of said lever members positioned on opposite sides of said upright support member or standard to position said tensile member support bars in downwardly directed relationship when the rack is in collapsed relationship and to lift, space, and substantially horizontally position said first and second tensile member support bars when said rack is in fully expanded relationship.

It is a further object of the present invention to provide a novel controllably expandable and collapsible rack (primarily intended for clothes airing or drying use, although not specifically so limited) wherein the upright vertical support member or standard is of substantially cylindrical, hollow, tubular configuration and wherein the slideable collars or rings are correspondingly shaped and sized.

It is a further object of the present invention to provide a novel controllably expandable and collapsible rack of the character referred to above wherein the lever members, fulcrum, and tensile member support bars are of hollow configuration for providing a high strength-to-weight ratio for the entire rack.

It is a further object of the present invention to provide novel auxiliary supporting means or supporting base means for rigidly mounting the entire device with respect to an underlying substantially horizontal ground surface (which shall also mean floor surface).

It is a further object of the present invention to provide a novel rack of the character set forth in the preceding object, wherein said supporting base means includes a telescopic engaging means adapted to be rigidly positioned in a stable manner with respect to the underlying substantially horizontal ground surface (which shall also mean floor surface).

It is a further object to provide a novel rack of the character set forth in the preceding object, wherein the telescopic engaging means is rigidly embedded within the horizontal ground surface and telescopically engages the lower end of the upright vertical support member or standard of the rack for effectively mounting same.

It is a further object to provide a novel rack of the character referred to in the third preceding object wherein said supporting means comprises a controllably collapsible base means adapted to be connected to said upright vertical support member or standard adjacent the bottom thereof and having lateral extension portions adapted to lie in a substantially horizontal plane for stable engagement with said substantially horizontal underlying ground or floor surface to support the entire rack in a stable manner anywhere, although this arrangement is particularly advantageous indoors where the device may be completely stored away when not in use, if desired.

It is a further object of the present invention to provide a novel rack of the character set forth in the preceding object, wherein said lateral extension portions of the collapsible base means are controllably collapsible or foldable into a compact configuration for convenient storage and portability.

Further objects are implicit in the detailed description which follows and which is to be considered as exemplary and not limiting, and said objects will be apparent to persons skilled in the art after a careful study of the said description.

For the purpose of clarifying the nature of the present invention, one basic form of the invention and several exemplary modifications of the supporting base means are illustrated in the figures of the accompanying three sheets of drawings and are described in detail hereinafter.

FIGURE 1 is a reduced-size perspective view showing one exemplary form of the invention in fully expanded position and supported by one particular type of supporting base means or ground surface coupling means above a ground surface comprising a fragmentarily shown surface of grass or turf.

FIGURE 2 is an enlarged fragmentary view, partly in elevation and partly in section, illustrating a modification of the supporting base means shown in FIGURE 1. This form is intended primarily for outdoor use, although not specifically so limited.

FIGURE 3 is a fragmentary perspective view illustrating another modification of the supporting base means intended primarily for indoor use, although not specifically so limited.

FIGURE 4 is an enlarged fragmentary view of one of the two oppositely positioned connection ends of each of the first and second tensile member support bars, taken in the direction of the arrow 4 of FIGURE 1 and illustrates the connection thereto of the corresponding outer linkage end of the corresponding one of the two sets of lever members. It should be clearly understood that each of the other three similar structures comprising the outer three connection ends of the first and second tensile member support bars, and the connection thereof to the corresponding three outer linkage ends of the other three lever members is substantially identical in construction and, therefore, this single view is exemplary of all. It should be noted that certain portions of the structure substantially behind the plane of the view are not shown for reasons of drawing simplification and clarity.

FIGURE 5 is an enlarged fragmentary view, partly in section and partly in elevation, of the pivotal connection of the fulcrum member to the lower member on line 40 5-5 of FIGURE 1 with certain structural portions substantially behind the plane of the view being removed for reasons of drawing simplification and clarity.

FIGURE 6 is an enlarged fragmentary, partly broken-away perspective view illustrating the detail of one exemplary structure for pivotally connecting the four longitudinal rigid fulcrum members (comprising first and second sets of two fulcrum members each) with respect to the normally upright vertical support member or standard. This view also illustrates the slideable connection of the inner pivotal connection ends of the two lever members of each of the two different sets thereof to the corresponding first or second ring or collar means for rack-opening and rack-closing reciprocation. It should be understood that the center portion of the vertical upright support member or standard (which is shown in phantom) is broken away and removed from this view for space conservation reasons.

FIGURE 7 is a fragmentary, partly broken-away elevation view further illustrating the means for immobilizing the attachment bracket shown in part at the top of FIGURE 6.

FIGURE 8 is a fragmentary view, partly in elevation and partly in section, of the two slideable collars or rings when in the vertically adjacent centrally positioned locked relationship shown in FIGURE 1 which maintains the rack in fully expanded relationship. This view illustrates one specific exemplary form of the retaining means for holding the slideable collars or rings in said relationship.

FIGURE 9 is a reduced-sized elevational view of the entire rack when in fully collapsed relationship with the collapsed tensile member support bars lying slightly outwardly angularly spaced relative to the upper end of the vertical support member or standard as allowed by the linkages connecting the connection ends thereof to the linkage ends of the corresponding lever members. Ac-

tually, said upwardly projecting angularly spaced connection ends of the tensile member support bars may be collapsed even further inwardly if desired for storage in an extremely small space volume configuration.

FIGURE 10 is a larger scale top plan view of FIGURE 9. It should be realized, as pointed out in connection with FIGURE 9, that the tensile member support bars can be easily collapsed even further inwardly from the at rest position shown in FIGURE 10 if desired.

FIGURE 11 is an elevational view, generally similar to FIGURE 1, but shows the rack in a partially collapsed relationship between the fully expanded relationship shown in FIGURE 1 and the fully collapsed, at rest, relationship shown in FIGURES 9 and 10.

Referring to the figures for exemplary purposes, one illustrative embodiment of the invention takes a typical form wherein it comprises a longitudinal, normally upright support member or standard, indicated generally by the reference numeral 21, which has a lower portion or bottom end 22 adapted to be rigidly supported in a firm, stable relationship with respect to an underlying ground surface, indicated generally by the reference numeral 23, and which in the specific example illustrated in FIGURE 1 comprises a grass or turf surface. The several different types of supporting means are generally designated by the reference numeral 24 in the case of FIGURE 1, 24A in the case of FIGURE 2, and 24B in the case of FIGURE 3, and each will be described in detail hereinafter.

The normally upright or vertical support member or standard 21, in the specific example illustrated, is of substantially cylindrical, hollow, tubular configuration and comprises the hollow cylindrical tube 25. However, the invention is not specifically so limited.

In the exemplary form illustrated, the normally upright vertical support member or standard 21 is effectively pivotally provided with a plurality of longitudinal rigid fulcrum members in several sets thereof, with each fulcrum member having a pivotal fulcrum connection means spaced from the pivotal connection of said fulcrum member with respect to the upright support member or standard 21 by a given distance which, in the preferred form of the invention, is equal for each of said fulcrum members.

In the exemplary form illustrated, said fulcrum members are four, in number and are designated generally by the reference numerals 26, 27, 28 and 29, respectively. It should be noted that, in the form illustrated, the fulcrum members 26 and 27 may be said to comprise a first set of said fulcrum members while the fulcrum members 28 and 29 may be said to comprise a second set of said fulcrum members. Furthermore, it should be noted that the disposition of said first and second sets of fulcrum members is such that the first set of fulcrum members 26 and 27 may be said to be effectively positioned on the opposite side of said vertical upright support member or standard 25 from said second set of fulcrum members 28 and 29.

In the specific example illustrated, the pivotal connection of the inner ends of the four fulcrum members 26, 27, 28 and 29 with respect to the normally upright support member or standard 21 is provided by way of novel attachment bracket means, generally designated by the reference numeral 31, which is fixedly attached to the tubular member 25 comprising the upright support member or standard 21 by top and bottom retainers comprising the circumferential enlargement 32 and the retaining cotter pin 33. The circumferential enlargement 32 lies below the cylindrical sleeve portion 34 of the attachment bracket 31 and supports same, while the cotter pin 33 lies through a hole 35 positioned immediately above the sleeve 34 and restrains it against upward movement. However, this is exemplary only, and various other means for mounting the attachment bracket means 31 on the cylindrical member 25 of the upright support standard 21 may be employed.

In the specific example illustrated the attachment bracket means 31 is provided with a plurality (in the example illustrated, four) bifurcated yoke portions 36 each angularly spaced around the longitudinal vertical axis of the upright support standard 21 and each being directed outwardly in a manner offset from a corresponding part of two corresponding angularly displaced planes coincident with said central axis of said support standard, and each having a directional component substantially parallel thereto. This is best shown in FIGURE 10 wherein each of said angularly displaced planes is designated by the reference numeral 37 and wherein it can be clearly seen that each of the four pairs of angularly displaced bifurcated yoke portions 36 is substantially parallel to, but offset from, a corresponding part of said two angularly displaced planes 37.

Each of the bifurcated yoke portions 36 has effective pivot pin means 38, as for example threaded fastener means, carried laterally therebetween and pivotally mounting a corresponding one of the four pivotal connection ends 39, 41, 42 and 43 of the corresponding ones of said fulcrum members 26, 27, 28 and 29.

The pivotal fulcrum connection means of the four fulcrum members 26, 27, 28 and 29 are indicated generally by the corresponding reference numerals 44, 45, 46 and 47 and are similar to each other so that only one need be shown in detail, as illustrated in FIGURE 5. These pivotal fulcrum connection means will be described in greater detail hereinafter.

It should also be noted that the preferred form of the invention includes first and second separately operable sets of lever members, in the form illustrated each set comprising two lever members, having inner pivotal connection ends, outer linkage ends, and intermediate fulcrum connection means-engageable portions.

In the specific exemplary form illustrated, the four lever members are indicated generally by the reference numerals 48, 49, 51 and 52. In the form illustrated, the two lever members 48 and 49 may be said to comprise the lever members of a first set of levers, while the two lever members 51 and 52 may be said to comprise the lever members of a second set thereof.

The intermediate fulcrum connection means-engageable portions of the four levers, 48 and 49 of the first set of levers and 51 and 52 of the second set of levers, are generally designated by the reference numerals 53 in the case of the lever 48, 54 in the case of the lever 49, 55 in the case of the lever 51, and 56 in the case of the lever 52, and each of these intermediate fulcrum connection means-engageable portions is pivotally connected to the corresponding pivotal fulcrum connection means 44, 45, 46 or 47, respectively, by corresponding effective pivot pin means 57, 58, 59 and 61, which, in the example illustrated, comprise threaded fastener means, although not specifically so limited.

Each of the four lever members 48 and 49 of the first set and 51 and 52 of the second set has an inner pivotal connection end 62, 63, 64 or 65, respectively, which is effectively pivotally attached with respect to corresponding first and second slidably collar or ring means 66 or 67, respectively, by corresponding pairs of outwardly projecting pivotal attachment bifurcated yoke portions designated by the reference numeral 68 in the case of the first slidable collar or ring means 66, and by the reference numeral 69 in the case of the second slidable collar or ring means 67.

The inner ends 62 and 63 of the pivotal lever members 48 and 49 of the first set thereof are pivotally connected to the bifurcated yoke portions 68 by the two effective pivot pin means 71, while the inner ends 64 and 65 of the lever members 51 and 52 of the other set thereof are pivotally connected by effective pivot pin means 72 to the bifurcated yoke portions 69, thus pivotally mounting all four of the lever members for pivotal movement around the effective pivot pin means 71 and 72 which, in the example illus-

trated, are shown as comprising threaded fastener means, although not specifically so limited.

Each of the slidable collar or ring means 66 and 67 is slidably mounted on the exterior of the tubular member 25 comprising the upright support standard 21 for vertical reciprocation in opposite directions in a first sense where they move away from each other for collapsing the entire rack in a general manner illustrated in steps as the apparatus moves through the sequence of positions shown in FIGURES 1 and 11 into the collapsed relationship shown in FIGURES 9 and 10. Each of said slidable collar or ring means 67 and 68 is also adapted for opposite reciprocation toward each other through a reverse sequence of positions from the fully closed at rest relationship shown in FIGURES 9 and 10 through an intermediate position such as that shown in FIGURE 11 into a fully expanded relationship such as shown in FIGURES 1 and 8, where the upper and lower slidable ring means 66 and 67 may be retained by the controllably releasable retaining means, indicated generally at 73 and 74.

In the example illustrated, each of said retaining means 73 and 74 comprises a resilient cam-shaped, normally outwardly projecting spring member 75 and 76, respectively, fastened with respect to the tubular member 25 comprising the vertical upright support standard 21 at a fixed fastening location, as indicated at 77 for illustrative purposes in connection with the upper retaining means 73, a similar but inverted arrangement being employed for the lower retaining means 74, so that each of the resilient cam-shaped spring members 75 and 76 normally projects outwardly until such time as it is depressed by the camming action of the corresponding slidable collar or ring 66 or 67 sliding downwardly or upwardly there-over, respectively, into an intermediate, vertically adjacent, centrally positioned, relationship as clearly shown in FIGURE 8 where said two spring members 75 and 76 again project outwardly and lock said upper and lower collars or rings 66 and 67 in said relationship, which corresponds to the fully expanded relationship of the rack shown in FIGURE 1. This position will be maintained until the retaining springs 75 and 76 are forcibly manually deflected inwardly through the corresponding slots 78 and 79 so as to be out of the path of upward or downward travel, respectively, of the corresponding rings 66 and 67 as they are slidably separated from the closed relationship shown in FIGURES 1 and 8, through the intermediate partially collapsed relationship shown in FIGURE 11, into the fully collapsed relationship shown in FIGURES 9 and 10.

Each of the four lever members 48, 49, 51 and 52, has a corresponding outer linkage end, indicated at 81 and 82 in the case of the two lever members 48 and 49 of the first set of said lever members, and indicated at 83 and 84 in the case of the two lever members 51 and 52 of the second set of lever members.

These outer linkage ends are provided with corresponding linkage means 85, 86, 87 and 88, respectively, for connection to corresponding connection ends 89, 91, 92, and 93, respectively, of the first and second tensile member support bars, generally designated by the reference numerals 94 and 95, respectively.

In the example illustrated, the linkage means 85, 86, 87 and 88 comprise effectively pivotally interconnected eye bolts and nuts. However, various other equivalent linkage means may be employed in lieu thereof.

The arrangement is such that when the first ring or collar means 66 is slidably moved upwardly from the position shown in FIGURE 1 through the intermediate position shown in FIGURE 11 toward the fully collapsed position shown in FIGURES 9 and 10, the outer linkage ends 81 and 82 of the first set of lever members 48 and 49 swing arcuately downwardly and inwardly in corresponding vertical planes, thus correspondingly moving the connection ends 89 and 91 of the first and second tensile member means 94 and 95 to a lower extreme position.

Conversely, downward slidable movement of the other ring or collar means 67 the position shown in FIGURE 1, through the intermediate position shown in FIGURE 11 into the fully collapsed at rest position shown in FIGURES 9 and 10, correspondingly causes arcuate upward and inward movement of the outer linkage ends 83 and 84 of the other two lever members 51 and 52 of the other set of said lever members, thus correspondingly elevating the adjacent connection ends 92 and 93 of the first and second tensile member support bars 94 and 95.

These opposed pivotal movements just described are brought about by the oppositely directed separating slidable movement of the first and second ring or collar means 66 and 67 and the cooperation of the corresponding first set of pivotal connection fulcrum means 44 and 45 and the second set of pivotal connection fulcrum means 46 and 47 with respect to the corresponding first and second sets of intermediate pivotal connection fulcrum means-engageable portions 53, 54, 55 and 56 of the corresponding first and second sets of lever members 48-49 and 51-52, respectively.

The above described action causes the two tensile member support bars 94 and 95 to assume substantially erect positions as shown in FIGURES 9 and 10 (although they are shown in an at rest, slightly outwardly diverging relationship which can be further collapsed) and causes the plurality of tensile members or clotheslines 96 connected between the first and second tensile member support bars 94 and 95 at a plurality of points spaced therealong, to hang downwardly in even, non-tangling loops such that the entire rack is adapted to be quickly and easily expanded and erected from the collapsed relationship shown in FIGURES 9 and 10 into the fully expanded relationship shown in FIGURE 1 and fragmentarily in FIGURE 8, where each of the tensile members or clotheslines 96 is stretched in taut, parallel relationship between the two tensile member support bars 94 and 95.

The arrangement is such that only two sliding engagements are provided in the entire apparatus and these comprise the separately operable sliding engagements of the upper slidable collar or ring means 66 and the lower slidable collar or ring means 67 with respect to the cylindrical tube 25 which forms the vertical upright support member of standard indicated generally at 21. All other connections of the movable elements of the apparatus are effectively pivotal connections. This contributes greatly to the ease of manual operation of the device in either the expanding or collapsing movement since this effectively minimizes the force required to be applied to either of the collar or ring means during the rack-expanding or rack-collapsing operation.

Furthermore, it should be clearly noted that each of the collar or ring means 66 and 67 is independently slidably moved and erects or collapses one-half of the expandable elements of the rack at a time, thus effectively greatly reducing the required force which must be applied to each of said slidable collar or ring means 66 or 67 during the rack-expanding or rack-collapsing operation.

Indeed, these two features—that is, the minimization of sliding friction during any particular operation, and the breaking of the expanding or collapsing operation into two steps each—are highly advantageous in that they reduce the amount of force required to be applied to either of the slidable collar or ring means 66 or 67 to a low value well within the strength capabilities of the average woman. This is greatly superior to prior art arrangements where multiple sliding elements are involved during a single erecting or expanding operation, which thus requires the application of a very substantial amount of force to the apparatus during the expanding operation, which is often virtually at the limit of, or beyond, the strength capabilities of the average woman.

The supporting means generally designated at 24 in FIGURE 1 may be said to comprise supporting base

means including telescopic engaging means, indicated generally at 97, comprising, in this exemplary form of the invention, the recess-defining portion or member 98 at the bottom of the hollow, cylindrical, tubular support standard 21 which received therein the upper end 99 of a projection-defining member 101, which has its lower pointed end 102 firmly buried in and supported in the ground surface 23. This provides a firm support for the support standard 21 and the entire rack and yet one which is of a readily removable nature when desired.

FIGURE 2 illustrates a slight modification of the supporting means or supporting base means, which is designated by the reference numeral 24A in this view. In this form of the invention, said supporting base means 24A includes the telescopic engaging means 97A which includes the recess-defining member 98A which, in this case, is partially buried in and imbedded in the ground surface 23A which, in this exemplary form, is shown as comprising concrete, although not specifically so limited. In this modification the recess-defining member 98A is upwardly open and receives the bottom end portion 22A of the upright support standard 21A, which corresponds to the upright vertical standard 21 of FIGURE 1, to provide a firm support. It should also be noted that a stop collar 103 is fastened by suitable fastening means 104 to the upright vertical support standard 21A at a position spaced above the bottom end 22A thereof so as to come into abutting contact with the open end of the recess-defining member 98A when in the engaged relationship shown in FIGURE 2. This provides a firm, rigid mounting for the support standard 21A, and the rack adapted to be carried thereabove, and yet one which is of a readily removable nature.

FIGURE 3 illustrates a further modification of the supporting means or supporting base means which is designated, in this case, by the reference numeral 24B and which is shown as comprising a base member 104' which is firmly fastened to the bottom end 22B of the upright vertical support standard 21B and which has the four bifurcated yoke portions 105 which are pivotally attached by effective pivot pin means 106, as for example threaded fasteners, to the inner ends of four lateral extension portions or members 107 and which have intermediate portions pivotally connected by effective pivot pin means 108, as for example threaded fasteners, to the four fulcrum members 109.

The four fulcrum members 109 have inner ends pivotally connected by effective pivot pin means 110, as for example threaded fastener means, to another set of four bifurcated yoke portions 111 of an attachment bracket 112 which is connected to a slidable ring 113 slidably mounted on the lower portion of the vertical upright support standard 21B.

This structure is generally similar in principle and operation to either of the previously described slidable collar or ring means 66 or 67 and operates in a manner such that upwardly slidable movement of the slidable ring 113 and the attachment bracket 112 after manual depression of the retaining spring 114 will cause each of the four lateral extension portions 107 to fold upwardly in the directions indicated by the broken line arrows 115 so as to lie very close to the upright support standard 21B in a substantially fully collapsed relationship generally similar to the collapsed relationship of the rack members shown in FIGURES 9 and 10 and described in detail hereinbefore. On the other hand, the ring 113 and the attachment bracket 112 may be slidably moved downwardly over the cam-shaped retaining spring 114 into a retained position such as is shown in FIGURE 3 which will have the effect of firmly and rigidly holding the four lateral extension portions 107 in the projecting horizontal planar relationship shown in FIGURE 3 for supported engagement with an underlying ground surface whereby to hold the upright support standard 21B in the upright position shown and in a very stable manner.

This form of the supporting base means is primarily intended for indoor use where the entire device is to be completely stored away between use periods, although it may be used under other circumstances and may even be used outdoors if desired.

Numerous modifications and variations exist within the broad scope and basic teachings of the present invention, and all of these are intended to be included herein as fully as if they were described and illustrated in detail. The figures and the specific description thereof set forth in this application are for the purpose of illustrating only and are not to be construed as limiting the present invention to the precise and detailed structure shown in the figures and specifically described herein. Rather, the real invention is intended to include any and all substantially equivalent constructions embodying the basic teachings and inventive concept of the present invention as set forth in the following claims.

What is claimed is:

1. An extensible and collapsible clothes hanging rack, comprising: a central support standard, adapted to be mounted in a vertical position, two pairs of elongated rigid fulcrum members pivotally connected at their inner ends to opposite sides of said support standard at a fixed position near its upper end, two pairs of elongated lever members positioned on opposite sides of said support standard and pivotally connected at fixed positions intermediate their ends to the outer ends of said fulcrum members, upper and lower collar means independently slidable vertically on said support standard and pivotally connected to the inner ends of said lever members, and a pair of tensile member support bars positioned on opposite sides of said support standard adapted to support a plurality of flexible tensile clothes hanging members suspended therebetween and universally connected near their respective ends to the outer ends of said lever members.

2. An extensible and collapsible clothes hanging rack,

comprising: a central support standard, adapted to be mounted in a vertical position, two pairs of elongated rigid fulcrum members pivotally connected at their inner ends to opposite sides of said support standard at a fixed position near its upper end, two pairs of elongated lever members positioned on opposite sides of said support standard and pivotally connected at fixed positions intermediate their ends to the outer ends of said fulcrum members, upper and lower collar means independently slidable vertically on said support standard and pivotally connected respectively to the inner ends of one adjacent pair of said lever members and to the inner ends of the other adjacent pair of said lever members, and a pair of tensile member support bars positioned on opposite sides of said support standard adapted to support a plurality of flexible tensile clothes hanging members suspended therebetween and universally connected near their respective ends to the outer ends of one of the said lever members connected to the said upper collar means and an adjacent one of the said lever members connected to the said lower collar means and to the outer ends of the other adjacent pair of said lever members.

3. An extensible and collapsible clothes hanging rack,

comprising: a central support standard, adapted to be mounted in a vertical position, two pairs of elongated rigid fulcrum members pivotally connected at their inner ends to opposite sides of said support standard at a fixed position near its upper end, two pairs of elongated lever members positioned on opposite sides of said support standard and pivotally connected at fixed positions intermediate their ends to the outer ends of said fulcrum members, upper and lower collar means independently slidable vertically on said support standard and pivotally connected respectively to the inner ends of one non-adjacent pair of said lever members and to the inner ends of the other non-adjacent pair of said lever members, and a pair of tensile member support bars posi-

tioned on opposite sides of said support standard adapted to support a plurality of flexible tensile clothes hanging members suspended therebetween and universally connected near their respective ends to the outer ends of one of the said lever members connected to the said upper collar means and an adjacent one of the said lever members connected to the said lower collar means and to the outer ends of the other adjacent pair of said lever members.

4. An extensible and collapsible clothes hanging rack as defined in claim 1, wherein said fulcrum members are pivotally connected to said support standard at a first set of points, lying in a plane, perpendicular to the longitudinal axis of said support standard, opposite ones of said points are displaced equidistant respectively on opposite sides of a first pair of vertical planes, coincident with said longitudinal axis, opposite pairs of said lever members lie respectively within said first pair of vertical planes, and opposite pairs of said fulcrum members are pivotally connected respectively to said lever members at a second set of points, displaced laterally of and on opposite sides of said lever members so that each of said fulcrum members lies in a vertical plane, coincident with one of said first set of points and parallel to one of said first pair of vertical planes.

5. In an extensible and collapsible clothes hanging rack as defined in claim 1, controllably releasable locking means for retaining said upper and lower slidable collar means in vertically adjacent centrally positioned relationship when the clothes hanging rack is fully extended.

6. An extensible and collapsible clothes hanging rack as defined in claim 5, wherein said controllably releasable locking means comprise upper and lower resilient, normally outwardly projecting spring means fastened

with respect to said support standard to engage and secure said upper slidable collar means in its lowest position on said support standard, and to engage and secure said lower slidable collar means in its highest position on said support standard.

7. In an extensible and collapsible clothes hanging rack having a central support standard and a pair of tensile member support bars adapted to support a plurality of flexible tensile clothes hanging members suspended therebetween and in the extended position of the rack to be disposed horizontally in a spaced apart relationship on opposite sides of said support standard and in the collapsed position of the rack to be disposed vertically closely adjacent and parallel to said support standard, first means connected to said support standard for moving one end of each of said tensile member support bars from said collapsed position to said extended position and from said extended position to said collapsed position, and second means connected to said support standard for so moving the other end of each of said tensile member support bars, said first and second means being operable independently of each other.
